United States Patent Office.

JOHN JENK, OF WASHINGTON, DISTRICT OF COLUMBIA.

Letters Patent No. 63,642; dated April 9, 1867.

IMPROVEMENT IN BUTTONS.

The Schedule referred to in these Letters Patent and making part of the same.

TO ALL WHOM IT MAY CONCERN:

Be it known that I, JOHN JENK, of the city and county of Washington, in the District of Columbia, have invented a new and useful Improvement in Buttons; and I do hereby declare the following to be a full and exact description of the same, reference being had to the accompanying drawings, which are made a part of this specification, and in which—

Figure 1 is a central section of a button, as applied to the garment illustrating my invention.

Figure 2 is a central section of a button illustrating a modification.

Figures 3, 4, 5, 6, 7, 8, and 9 are detail views, hereinafter specifically referred to.

Similar letters of reference indicate corresponding parts in the several figures.

In the button which forms the subject of this invention a shouldered shank has secured upon one of its ends a disk or other laterally-projecting fixture, and receives the head of the button after being inserted through the garment at the desired point of attachment. The present improvement consists in the means whereby the head of the button is retained upon the end of the shank.

In order that others skilled in the art to which my invention appertains may be enabled to fully understand and use the same, I will proceed to describe it in detail.

In the drawings, *a* represents a rigid shank of metal or other suitable material, and *b* is a disk or bar fixed upon the end thereof, by riveting or otherwise. Figs. 3 and 4 are top views, the former representing a flat piece or bar, and the latter a disk as applied to the end of the shank *a*. The other end of the shank *a* may be formed with a barb or otherwise adapted to penetrate the cloth, or it may be formed with a hemispherical head, as shown in fig. 7; in any case it has essentially a shoulder, *a'*; *c* represents the metallic or other covering for the head of the button. *d* is the filling of the button-head, and *e* is the back plate thereof. Between the filling and the back plate is confined a diaphragm, *f*, which may be a disk of rubber, leather, cloth, or analogous material, and which, if preferred, may be provided with a seat in the inner side of the back plate *e*, as shown in fig. 7. An aperture, *g*, square or circular, extends through the back plate *e*, as seen in figs. 8 and 9, and said aperture extends into the filling *d* of the button-head, as shown in figs. 1 and 2. In constructing the button, an incision simply, as shown in fig. 5, or two incisions, in the form of a cross, as in fig. 6, may be made in the centre of the diaphragm *f*, but these incisions are only necessary when the end of the shank is blunt, inasmuch as a pointed shank will make the necessary opening in the diaphragm when the button-head is applied. The office of the diaphragm is obvious. The shank *a* is passed through the cloth, and the disk or fixture *b* pressed snugly up against the inner surface. The button-head *c d e* is then applied to the extremity of the shank *a*, which projects from the outer surface of the cloth. The shank *a* enters the aperture *g* of the button-head, the head of the shank being adapted to penetrate the diaphragm *f*, as before stated. As soon as the head of the shank is fairly introduced into the button-head, the diaphragm *f* closes about the shank and upon the shoulder *a'*, and effectually prevents the withdrawal of the shank from the button-head.

The button is intended for permanent application, and the herein-described means for attaining the desired end are believed to be more simple, cheap, and effective than those heretofore devised. An additional shoulder, *a''*, may, if desired, be formed upon the shank *a* for the purpose of clamping a washer, *a'*, against the back plate *e* of the button-head, as shown in fig. 2, in order to give firmness and steadiness to the button when applied.

Having thus described my invention, the following is what I claim as new, and desire to secure by Letters Patent:

I claim the diaphragm *f*, confined within the head of a button, substantially as described, and employed in connection with the shouldered shank *a* and disk or fixed piece *b*, in the manner and for the purpose set forth.

JOHN JENK.
